UNITED STATES PATENT OFFICE.

PAUL H. BERGER, OF BRONX, NEW YORK.

TOY PISTOL.

Application filed October 20, 1927. Serial No. 227,528.

The present invention refers to toys and more particularly spoken of as toy guns of the pistol character, and its object is to provide an improved kind of a toy gun or pistol, in which by the action of a spring a missile is hurled away and at the same time a cartridge is fired so as to produce a most natural imitation of the real pistol action. It is further an object of the present invention to simplify the construction of toy pistols of the class described so as to make them cheaper in the manufacture and at the same time more reliable in their action.

In order to carry out those purposes, an arm made out of a piece of resilient wire is fixed with its looped front end to the front end of the barrel imitating part of the body of the toy pistols where as the rear-end of this arm is shaped to form a sling, loop or ring to receive the missile which may be a coin or a ball or the like, and near to the rear-end the arm is provided with an arrest for the hook of the wire made trigger. Further it is an important feature of my invention that on the middle part of the top side of the barrel of the toy gun an arm is hinged adapted to swing round the hinging point and further adapted to limit the swing of the first mentioned resilient arm. Finally it is a characteristic feature of my invention that on the middle part of the said swinging resilient arm and of the swinging end of the said limiting arm two pieces of flat metal or the like are fixed which are adapted to clash together at the end of the shooting swing of the first mentioned arm and to fire a paper cartridge or fire cracker which may be placed on one of the two metal plates.

In order to make more clear the nature of my invention, a preferred embodiment of it is shown in the annexed drawing whereby the drawing shows in full lines the new toy gun in the position ready for firing, whereas the dotted lines show the position of different parts after the gun has been shot.

In the shown embodiment of my new and improved toy gun the main body is made out of wood or of metal as a single piece or in two or more parts which for instance may have the form of two flat shells of sheet metal which are affixed together in the middle place of the toy. This main body consists of the handle 1 and the barrel-imitation part 2. At the front end of the latter is affixed the arm 3 made out of a resilient wire with a loop 4 near its front end, to increase its resiliency. The

middle part of arm 3 is bent twice so as to form a double knee 5, whereas the rear end of the arm 3 is bent into the form of a ring 6, adapted to bear a rubber ball 7 or other similar missile. Near the closing point of the ring the end of the wire is bent into the shape of a sling or loop 8 and fastened to the arm 3 by the means of a metal clamp or fastener 9. The trigger is likewise made out of a piece of resilient wire, which is bent into an open ring or loop 10 and in the barrel part of the main body a lower slot 11 and an upper slot 12 are provided, so that the longer arm 13 at the one side of the trigger ring can reach through the barrel part and can catch with its upper hook 14 into the sling or loop 8. The other end 15 of the trigger ring is simply hooked into the left side corner of the lower slot 11, whereas the right-side corner of this slot acts as the turning point or pivot of the trigger.

In the middle of the upper part of the side walls of the barrel are provided with two depressed holes or grooves 16 into which engage the ends of the arm 17. This arm has the form of an elongated loop, which embraces the shooting arm 3, the ends of the arm being hooked into the holes 16, whereas the swinging upper part is bent upwardly somewhat and provided with a piece of flat metal 18. The double bent knee 5 is provided likewise with a piece of metal 19 preferably shaped so as to form a pan with a somewhat higher brim on which pan may be deposited the paper cartridge or fire cracker 20 to be fired.

The before described construction results in the following operation of my improved toy gun: The resilient arm 3 is bent down over the barrel part 2 and fixed in this tensioned position by hooking the sling 8 over the hook 14 of the trigger. Then the ball 7 is placed on the ring 6 and a paper cartridge or fire cracker 20 is put on the pan 19 whilst the arm 17 may be in the lowered position, as shown in Figure 1 in full lines. If then the trigger ring 10 is pulled into the position shown by dotted lines, then its longer arm 13 with the hook 14 swings to the left side and gives free the sling 8, whereupon the tensioned arm 3 snaps upwardly and hurls the ball 7 away towards the goal. The free swinging end of the arm 17 is likewise swung upwardly by the rising arm 3 until the movement of both parts is limited by the clashing together of the metallic hammer piece 18 and the metallic pan 19, as indicated in dotted

lines. The clashing together of those two pieces of metal causes the firing of the cartridge of fire cracker 20.

It is understood that the scope of the present invention is not limited to the embodiment as illustrated and described above in detail, but there may be made changes and variations. For instance it has been mentioned already above that the missile may be 10 a coin, which is placed in vertical position into a narrow slot formed sling at the swinging end of the resilient arm. Another possible change of the construction would consist straightening out the double knee 5 and place 15 the cartridge holding pan 19 on the middle part of a straight-shaped swinging arm, replacing at the same time the loop-formed double arm 17 by a simple one-stem arm which is guided in a hole in the cartridge 20 holding pan, the free end of which one-stem arm bears the hammer or metal block for firing the cartridge.

What I claim is:

1. In a toy pistol: a barrel; a resilient arm affixed to said barrel; a pan for holding paper cartridges on said arm; a swinging arm hinged to the said barrel the end of which swinging arm coacts with said pan and at the same time limiting the upward movement of said resilient arm when the latter is released.

2. In a toy pistol: a barrel; a resilient arm affixed to the said barrel; a swinging arm hinged to the said barrel and adapted to limit the movement of the said resilient arm; a pan for holding a cartridge at the middle part of the resilient arm and a hammer like block at the free end of the swinging arm, adapted to strike on the cartridge so as to 40 fire it, when the resilient arm is released.

3. In a toy pistol: a barrel; a wire made resilient arm affixed to the front part of the said barrel and having a coiled loop to increase its resiliency; a swinging arm hinged 45 to the said barrel and adapted to limit the movement of the said resilient arm; a cartridge holding pan and hammer-like block on the said resilient arm and on the said swinging arm respectively for firing the cartridge when the resilient arm is released.

4. In a toy pistol; a barrel; a resilient arm affixed to the said barrel; a loop-shaped swinging arm hinged to the barrel and embracing the said resilient arm so as to limit its movement when it is released; and means 55 on the said resilient arm coacting with means on the said swinging arm for firing a cartridge, when the resilient arm is released.

5. In a toy pistol; a barrel; a wire made resilient arm affixed to the front end of the 60 barrel and extending along the upper side of the said barrel; a coiled loop in the arm near to its front end, to increase its resiliency; a shoulder formed in the middle part of the said arm; a loop shaped swinging arm, hinged 65 to the middle part of the barrel and embracing the said resilient arm so as to limit its movement when it is released; a cartridge holding pan on the shoulder of the resilient arm and a hammer like block at the end of the 70 said swinging arm, adapted to clash together and to fire the cartridge, when the resilient arm is released.

6. In a toy pistol: a barrel; a resilient arm affixed to the said barrel; a swinging arm 75 hinged to the said barrel and adapted to limit the movement of the said resilient arm; means on the said resilient arm coacting with means on the said swinging arm for firing a cartridge when the resilient arm is released; 80 means at the free end of the resilient arm for holding a missile and for hurling it away when the resilient arm is released.

7. In a toy pistol: a barrel; a resilient arm affixed to the said barrel; a swinging arm 85 hinged to the said barrel and adapted to limit the movement of the said resilient arm; a wire made trigger at the lower side of the barrel, adapted to hold the resilient arm in tensioned position or to release it; means on 90 the said resilient arm coacting with means on the said swinging arm for firing a cartridge when the resilient arm is released; means at the free end of the resilient arm for holding a missile and for hurling it away when the 95 resilient arm is released.

Signed at New York in the county of Bronx and State of New York this 18th day of August, A. D. 1927.

PAUL H. BERGER.
